(57) **CLAIM**

The ornamental design for an elongated skin toning device, as shown and described.

DESCRIPTION

FIG. 1 is a front perspective view of an embodiment of an elongated skin toning device;

FIG. 2 is a front elevational view of the elongated skin toning device shown in FIG. 1;

FIG. 3 is a rear elevational view of the elongated skin toning device shown in FIG. 1;

FIG. 4 is a right side elevational view of the elongated skin toning device shown in FIG. 1;

FIG. 5 is a left side elevational view of the elongated skin toning device shown in FIG. 1;

FIG. 6 is a top plan view of the elongated skin toning device shown in FIG. 1;

FIG. 7 is a bottom plan view of the elongated skin toning device shown in FIG. 1;

FIG. 8 is a rear perspective view of the elongated skin toning device shown in FIG. 1;

FIG. 9 is a front perspective view of another embodiment of an elongated skin toning device with a cap on a distal end thereof;

FIG. 10 is a front elevational view of the elongated skin toning device shown in FIG. 9;

FIG. 11 is a rear elevational view of the elongated skin toning device shown in FIG. 9;

FIG. 12 is a right side elevational view of the elongated skin toning device shown in FIG. 9;

FIG. 13 is a left side elevational view of the elongated skin toning device shown in FIG. 9;

FIG. 14 is a top plan view of the elongated skin toning device shown in FIG. 9; and

FIG. 15 is a bottom plan view of the elongated skin toning device shown in FIG. 9; and,

FIG. 16 is a rear perspective view of the elongated skin toning device shown in FIG. 9.

The broken lines in the drawings depict portions of the elongated skin toning device and form no part of the claimed design.
